(57) **CLAIM**

The ornamental design for a power cable, as shown.

DESCRIPTION

FIG. 1 is a first end view of a power cable including a first connector according our design;

FIG. 2 is a second end view a power cable including a second connector thereof;

FIG. 3 is a side view of the cable thereof;

FIG. 4 is a top view of the cable thereof;

FIG. 5 is a perspective view of the cable and the first connector thereof; and,

FIG. 6 is a perspective view of the cable and the second connector thereof.

The power cable is shown with a symbolic break in its length. The appearance of any portion of the article between the break lines forms no part of the claimed design.
